United States Patent

Des. 241,490
Patented Sept. 21, 1976

241,490

MODULAR DISPLAY TABLE OR SIMILAR ARTICLE

James H. Karlin, Streamwood, Ill., assignor to
Motorola, Inc., Schaumburg, Ill.

Filed Jan. 9, 1975, Ser. No. 539,895

Term of patent 14 years

Int. Cl. D6—04

U.S. Cl. D6—158

FIG. 1 is a perspective view of a modular display table or similar article showing the front, one side and the top of my new design;

FIG. 2 is an elevation view of the front side of the modular display table shown in FIG. 1;

FIG. 3 is an elevation view of the left side of the modular display table shown in FIG. 1; and

FIG. 4 is an elevation view of the rear side of the modular display table shown in FIG. 1.

I claim:

The ornamental design for a modular display table or similar article, substantially as shown.
